UNITED STATES PATENT OFFICE

ADOLPH SELIKOWITZ, OF BROOKLYN, NEW YORK, ASSIGNOR TO METROPOLITAN IMPORTING & MFG. CO., OF NEW YORK, N. Y., A CORPORATION OF NEW YORK

COMBINATION DISPLAY AND INFORMATION DEVICE

Application filed July 2, 1931. Serial No. 548,316.

This invention relates to a combination display and information device such as a picture, print, sign or the like equipped with a calendar, legend card or the like, and has generally in view to provide a device of this character embodying a construction whereby the information element, such as a calendar or legend card, is movable to concealed and exposed positions relative to the picture or other display element.

A special object of the invention is to provide a device of the character mentioned which may be produced conveniently and economically from sheet material such as cardboard or the like, and which is strong and durable and unlikely to become damaged by reason of repeated manipulations of the information element to exposed and concealed positions.

According to the invention a base element is recessed to receive the information element and to serve as a backing for the picture or the like, and in this connection another object of the invention is to so combine the display element with the base element that said elements cooperate with each other to afford a substantially continuous and smooth support for the picture or the like when the display element is in a concealed position within the recess of the base element.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the drawings, wherein like characters of reference denote corresponding parts in the different views:

Figure 1 is a front elevation of a display device constructed in accordance with one practical embodiment of the invention;

Figure 2 is a view similar to Figure 1 showing the picture element of the device removed to disclose the underlying structure;

Figure 3 is a view similar to Figure 2 showing

the information element in its exposed position;

Figure 4 is a cross section on the line 4—4 of Figure 1;

Figure 5 is a section along line 5—5 in Fig. 2.

As shown in the drawings, the device comprises a backing 11, a base element 10 composed of two superposed sheets 27 and 28, preferably glued together, a frame superimposed thereon, and a picture or the like 13 contained within the frame and supported by the base element.

Although the parts of the device may be formed from any material or materials desired into any desired size and shape, the base element 10, the backing 11 and the frame 12 are formed preferably from cardboard, or equivalent material, into rectangular shape as shown, and they preferably are formed of equal length and width whereby their edges are disposed flush with one another when they are assembled in superimposed relation.

The frame 12 which may be of any suitable thickness and width, is glued or otherwise suitably fastened against the front face of the front sheet 28 of the base element to enclose the picture or the like 13, and the picture, which is of a size to neatly fit within said frame, likewise is glued or otherwise fastened against the front face of the front sheet 28 of the base element either at a plurality of points or, preferably, along a line extending across the top thereof, whereby its lower portion may be lifted whenever desired to afford access to the underlying parts of the device.

Formed through the sheets 27, 28 of the base element is a recess 14 for the reception of a thermometer or the like designated as 16. However, the provision of the recess 14 for the reception of the thermometer or the like is optional and it may be provided at any desired location, preferably at some point such that the opening 19 formed through the picture to render the thermometer visible does not mar the picture and such that the thermometer or the like adds to rather than

detracts from the attractiveness of the device.

The rear sheet 27 of the base element is cut to provide a recess 15 to accommodate a 5 slide 17 of corresponding size and shape, whereas the front sheet 28 is similarly recessed, as at 29, to accommodate a calendar or other information element secured to said slide.

10 While the recess 15 may be of any desired size and shape to accommodate the slide 17 of similar size and shape, it is preferably of inverted T-shape as shown and includes a relatively wide bottom portion 20 opening 15 through the lower edge of the sheet 27, and a narrow leg portion 21 opening at its lower end into the portion 20 medially thereof and extending upwardly into the sheet 27 any suitable or desired distance.

20 The slide 17 which, as aforesaid, corresponds in size and shape to the recess 15, is, therefore, of inverted T-shape and inclusive of a relatively wide bottom portion 22 and a medial upwardly extending leg portion 23 to be received in the corresponding portions 20 and 21, respectively, of the recess 15 when the slide is in a concealed position. In fact the slide may be and preferably is constituted by the portion of the rear sheet 27 of the base element that is cut therefrom to provide the recess 15, the same being movable between the concealed position mentioned beneath the picture 13 and the exposed position illustrated in Figure 3 with 25 the relatively wide bottom portion thereof extending below the lower edge of the base element and the frame, in which connection it will be observed that the leg portions 20 and 23 of the recess and the slide are of a 30 length such that when the bottom portion 22 of the slide is substantially completely withdrawn from the lower portion 20 of the recess the upper portion of the leg of the slide remains in the leg portion of the recess 45 to maintain the alignment of the slide with the recess whereby the former may readily be moved upwardly to its concealed position within the latter.

The backing 11 is glued or otherwise suitably secured against the rear face of the rear sheet 27 of the base element and serves both to stiffen the device and to close the rear sides of the recesses 14 and 15.

50 While any suitable means may be provided to limit downward movement of the slide beyond its exposed position shown in Figure 3, a simple arrangement to accomplish this purpose is illustrated in the present instance as comprising a longitudinally extending slot 55 24 formed in the leg portion 23 of the slide and a stop element 25 carried by the backing 11 and projecting into said slot for cooperation with the edge of the slide forming the upper limit of said slot, the stop element 60 being so disposed and the slot being of such

length that the edge of the slide forming the upper limit of the slot engages the stop element and limits further downward movement of the slide when any desired part of the lower portion 23 thereof becomes exposed 70 at the bottom of the device.

As has already been stated, the front sheet 28 has a recess cut therein at 29 to accommodate the calendar, or other information element, 30 suitably mounted on the portion 22 75 of the slide 17.

Suitably fastened to the slide 17 and extending below the bottom portion 22 thereof is a ribbon or tab 26 affording a finger grip element for facility in withdrawing the slide from its frictionally retained concealed position within the recess 15 to its exposed position. Because of the frictional engagement of the slide within recess 15, the stop 80 25 may, if desired, entirely be dispensed with.

Regarding assembly and disassembly of the slide with and from the base element, it is apparent that this may be effected at any time after the backing and the frame have been fastened to the base element simply by moving the slide to approximately its exposed position and flexing the upper end of the leg portion 23 outwardly to clear the stop element, whereupon the slide may be 85 slid either inwardly or outwardly.

The device represents an attractive and useful novelty and has special utility as an advertising medium, as the picture 13 may appropriately apply to the goods of a concern giving away or selling the device and the advertiser's name as well as other information may be applied to the picture or to some other part of the device.

90 From the foregoing description considered in connection with the accompanying drawings it is believed that the construction, operation and advantages of the device will be clearly understood. It is desired to point out, however, that while a certain specific embodiment of the invention has been illustrated and described, the same is readily capable of embodiment in other in mechanical structures within the spirit and scope of the invention as defined in the appended claims.

105 I claim:

1. A display device of the character described comprising a base element composed of front and rear superimposed sheets of material, the rear sheet having a recess formed therein, a backing fastened against the rear face of said rear sheet and extending across said recess, a slide movable into and from said recess, an information element mounted upon the front face of said slide, the front sheet having a recess to accommodate said information element, and a picture element superimposed upon said front sheet in covering relation to the recess therein.

115 2. A display device of the character described comprising a base element composed 120

of front and rear superimposed sheets of material, the rear sheet having a recess formed therein for the accommodation of a slide element, a slide element movable into and from said recess, an information element mounted on the front face of said slide element, the front sheet having a recess to accommodate said information element, means at the rear side of the rear sheet extending across the recess in said sheet in closing relation thereto, and means at the front side of the front sheet extending across the recess therein in closing relation thereto.

3. A display device of the character described comprising a base element composed of front and rear superimposed sheets of material, the rear sheet having a recess formed therein and opening through an edge thereof for the accommodation of a slide element, a slide element movable into and from said recess, an information element mounted on the front face of said slide element, the front sheet having a recess to accommodate said information element, means at the rear side of the rear sheet extending across and closing the recess therein, means at the front side of the front sheet extending across and closing the recess therein, and means to prevent complete withdrawal of the slide element from the recess in the rear sheet through the mouth of said recess where it opens through the edge of the sheet.

In testimony whereof I affix my signature.
ADOLPH SELIKOWITZ.
